United States Patent Office

Des. 227,178

Patented June 5, 1973

227,178

COOKING GRILL

Roland L. Duning, Indianapolis, Ind., assignor to Burger
Chef Systems, Inc. (BC), Indianapolis, Ind.

Filed Mar. 26, 1971, Ser. No. 128,640

Term of patent 14 years

Int. Cl. D7—02

U.S. Cl. D81—10

FIG. 1.

FIG. 2.

FIG. 3.

FIG. 4.

FIG. 1 is a top plan view of a cooking grill in accordance with my new design;

FIG. 2 is a rear elevational view thereof;

FIG. 3 is an elevational view of one side thereof, the other side being a mirror image of the side shown; and

FIG. 4 is a front elevational view thereof.

I claim:

The ornamental design for a cooking grill, as shown and described.
